TRANSFORMING DIE

Benjamin Burvenick, Richmond Hill, N. Y.,
assignor to Lalance & Grosjean Corpora-
tion, New York, N. Y., a corporation of New
York

Application February 20, 1936, Serial No. 64,912

9 Claims. (Cl. 113—44)

This invention relates to a shaping device or die by which hollow metallic blanks are shaped or transformed into articles of different forms, and which serves adequately for producing utensils.

The principal object of the invention is the provision of means suitable for quickly and cheaply transforming blanks of the indicated character, while cold, into articles of any desired size and shape or form with a neat finish and appearance.

A further object of the invention is the provision of a device of the indicated character which is simple, easily operated and of efficient and substantial design.

The nature of the invention and its distinguishing features and advantages will appear when the specification is read in conjunction with the accompanying drawing, in which

Figure 1 is a vertical section showing the features of the invention, a blank being shown in position preparatory to being forced into the die;

Fig. 2 is a view similar to Fig. 1 but showing the blank forced into the die and the plunger in operation;

Fig. 3 is a view similar to Fig. 1 but showing the plunger in action exerting pressure on the conformable substance in the blank to complete the transformation into an article of the desired shape;

Fig. 4 is a section on the line 4—4 of Fig. 1;

Fig. 5 is a view looking down on the plunger;

Fig. 6 is a top view of a blank used for producing a certain article;

Fig. 7 is a top view of an article produced from the blank shown in Fig. 6 by the use of the invention.

Referring now more particularly to the several views of the drawing, it will be apparent that in accordance with the invention use is made of a die 10 in the form of a block. The block has a cavity or recess 11 therein conforming to the exterior contour of the article to be formed. The block has a groove 12 to accommodate suitable clamps 13 which position the block to the bed 14 of a double-action press. In the present instance the cavity or recess 11 is square with round corners. The bottom of the cavity or recess 11 may be defined by a removable section 15 constituting a part of the die, said section 15 being dished so as to provide a rounded bottom to the article to be formed. Use is made of a pressure element 16 which is movable up and down with respect to the die 10. The element 16 consists of a plate section 17 which is horizontally disposed and pressure sections 18 which

are suspended from the section 17 on the under side thereof so as to be movable into and out of pressure-exerting position. Each of the sections 18 is of U shape in horizontal section, as shown most clearly in Fig. 4. Each section 18 is suspended for movement by means of a pivot 19 whose opposite ends are secured or journaled in lugs 20 respectively on the under side of the plate section 17. The plate section 17 has a square opening 21 therein to accommodate a second pressure element 22 in the form of a plunger. The element 22 is movable up and down by any suitable means forming a part of the press. The element or plunger 22 is square in horizontal transverse section with round corners, as indicated in Fig. 5. The pressure sections 18 when brought together in pressure-exerting relationship constitute a hollow structure, the interior of which is square with rounded corners and the internal area thereof being smaller than the area of the opening 21 and also the area of the element 22. The bottom of the element 22 is round at the four sides to conform to the shape of the forming surface of the die section 15. In the downward movement of the element 22 after the element 16 has come to rest, the element 22 acts on the upper inner edge portions of the sections 18, causing them to move on their pivots 19 to positions at right angles to their pressure-exerting positions.

In the present instance use is made of a blank 23 of metal, the same being cylindrical and having a bottom rounded at the cylindrical wall of the blank. The blank 23 is therefore in the form of a vessel or hollow body. In accordance with the invention, in order to transform the blank into an article, such as a cooking utensil, of the desired shape, the blank 23 is filled with a suitable conformable substance 24, which in the present instance is wax. The substance 24 when subjected to pressure forces the walls of the blank 23 evenly in all directions. The blank used in horizontal cross-sectional size is larger than that of the cavity or recess 11 in the die 10.

The operation of the device is as follows. A blank 23 of the indicated character filled with wax or equivalent substance is placed on top of the die 10 in registry with the cavity or recess 11. The pressure elements 16 and 22 are both elevated and the pressure sections 18 of the element 16 are engaged with the upper end of the blank 23 as indicated in Fig. 1. The pressure element 16 is then brought downwardly which exerts an endwise pressure on the blank 23 forcing the same into the recess 11 nearly but not all the

way in, whereupon the element 16 comes to rest. The pressure element 22 moves downwardly causing the sections 18 to swing outwardly out of engagement with the blank 23. The element 22 continues to move downwardly so as to exert pressure on the substance 24 causing the blank to move fully into the recess 11 and, at the same time, transforming the shape of the blank to conform to the contour of the recess 11, thereby producing a hollow vessel square in cross section with rounded corners, as illustrated in Fig. 7, and with a flat bottom except at the four sides the same being rounded at these points. The bottom section 15 of the die 15 may be pushed upwardly by reason of the opening 25 in the bed 14 so as to remove the formed article from the die.

Attention is called to the fact that the pressure sections 18 when brought together provide means to effectively bear down on the cylindrical wall of the blank due to the fact that the interior shape thereof is different from the shape of the blank, the former being square while the latter is round. This makes it necessary to swing the sections 18 outwardly after they have forced the blank into the die cavity, to provide clearance for the plunger 22, in order that the latter may complete the transformation of the blank into the finished article A.

30 I claim:

1. A transforming device comprising a die having a recess conforming to the exterior contour of the article to be formed, a pressure element movable with respect to the die and having movable means which in normal position serve to engage and force a hollow blank filled with conformable substance into said recess, and a second pressure element movable with respect to said die and said pressure element which acts 35 on said means to move the same out of engagement with said blank, and also to exert pressure on said substance while said blank is in said recess, to transform the blank into an article approximating the shape of said recess.

2. In a transforming device, a movable pressure element having an opening therein, and also having movable pressure sections at said opening pivoted thereto, said sections being engageable with a blank to force the same into a die recess upon the movement of said element with respect thereto, and means movable through said opening to cause the movement of said sections out of engagement with said blank.

3. In a transforming device, a movable pressure element having an opening therein, and also having movable pressure sections pivoted at said opening, said sections being engageable with a blank to force the same into a die recess upon the movement of said element with respect thereto, and a plunger movable through said opening to cause the movement of said sections out of engagement with said blank and to exert pressure on said blank to cause it to conform 55 with the shape of said recess.

4. In a transforming device, a movable element consisting of a plate section having an

opening, and pressure sections suspended from the underside of said plate section at said opening and movable with respect to said plate section, said pressure sections being engageable with a blank to force the latter into a die recess upon the movement of said element with respect thereto, and means movable through the opening to move said pressure sections out of engagement with said blank.

5. In a transforming device, a movable element consisting of a plate section having an opening, and pressure sections suspended from the underside of said plate section at said opening and movable on horizontal axes with respect to said plate section, said pressure sections being engageable with a blank to force the latter into a die recess upon the movement of said element with respect thereto, and a plunger movable through the opening to move said pressure sections out of engagement with said blank.

6. In a transforming device, a movable element consisting of a plate section having an opening, and pressure sections suspended from the underside of said plate section at said opening and movable with respect to said plate section, said pressure sections being of a cross-sectional shape different from that of a blank, said pressure sections being engageable with said blank to force the latter into a die recess upon the movement of said element with respect thereto, and means movable through said opening to move said pressure sections out of engagement with said blank.

7. In a device for transforming a hollow blank of one shape into a hollow article of another shape, pressure exerting sections swingable into and out of pressure exerting positions, said sections in their pressure exerting positions constituting a hollow structure having contact surfaces wider than the thickness of the wall of said blank to effectually exert pressure on the upper end of the wall of said blank, and means for moving said pressure exerting sections out of engagement with said blank.

8. In a transforming device, a movable pressure element having an opening therein, and also having movable pressure sections pivoted at said opening, said pressure sections being engageable with a blank to force the same into a die recess upon the movement of said element with respect thereto and a plunger movable through said opening to pivot said pressure member out of engagement with said blank and to exert pressure on said blank to transform into the shape of the recess.

9. A transforming device comprising a die having a recess conforming to the exterior contour of an article to be formed, a pressure element movable with respect to the die and having movable seating means pivoted to the bottom thereof, and adapted to seat a hollow blank into said recess, a plunger movable through said pressure element to disengage said seating means and to exert pressure on said blank to conform it to the shape of said recess.

BENJAMIN BURVENICK.
